UNITED STATES PATENT OFFICE.

MANNING A. KING, OF NEW YORK, N. Y.

IMPROVEMENT IN SEWING-MACHINES FOR QUILTING.

Specification forming part of Letters Patent No. 151,886, dated June 9, 1874; application filed January 10, 1874.

To all whom it may concern:

Be it known that I, MANNING A. KING, of the city, county, and State of New York, have invented certain Improvements in Sewing-Machines for Quilting, of which the following is a specification:

This invention relates to quilting-machines in which a carriage, having connected with it the needle-bar and its series of needles, presser-feet, and shuttle-carriers, has a reciprocating traversing motion, while the material to be sewed is passed at right angles to such motion under the needles, by means of feed-rollers and drawing-rollers arranged the one in front and the other in rear of the machine, such traversing motion of the carriage and direct feed of the material causing the stitches to be made in zigzag lines, as required. The invention consists in various combinations of mechanism, whereby great simplicity, durability, and efficiency are attained, the same including a ratchet-feed in which an intermittent revolving motion is kept up by reversely moving and reciprocating dogs controlled by a single pattern-wheel; also including two pattern wheels or cams on the same shaft, for operating in their proper relation both the feeding mechanism and traversing carriage; likewise, sundry combinations connected with the driving of said parts, and the operation of the shuttle-driver and presser foot or feet.

In the accompanying drawings, which form part of this specification, Figure 1 represents a front view of the machine, and Fig. 2 a plan of the same. Fig. 3 is a side view thereof, and Fig. 4 a vertical transverse section on the irregular line *x x*. Fig. 5 is a further vertical transverse section in part, mainly in illustration of the mechanical devices for actuating the feed and traversing carriage. Fig. 6 is a vertical longitudinal section, in part on the line *y y*. Fig. 7 is a view similar to Fig. 4, but on a larger scale of the needle-bar, with presser-foot and means for operating the latter. Fig. 8 is a vertical longitudinal section on the line *z z* of the traversing carriage, with shuttle-operating attachment, and Fig. 9 an inverted plan or under view of the same in part.

Similar letters of reference indicate corresponding parts in all the figures.

A is the main frame of the machine, and B

the primary or driving revolving shaft. C is the traversing carriage, supported by rollers, and D the needle-bar, provided with a series of needles, *b b*, arranged in rows one before the other, and with the needles of the one row directly, or in straight lines relatively to the feed, behind the needles of the other or front row. E E are the feed-rolls, between which the material to be quilted is introduced for passage over the table F and carriage C and under the needles, to and through or between the drawing-rolls G, said feed and drawing rolls moving in common by means of a connecting endless chain, H. The carriage C has a reciprocating traversing motion transversely to such direct feed of the material to be quilted, for the purpose of making the stitches in zigzag or irregular lines, as required. The means of traversing said carriage are as follows: On the shaft B is a partial screw, H*, which gives motion at intervals—that is, once during each revolution of said shaft—to a worm-wheel, I, fast on a revolving shaft or stud, *c*, which is adjustable in a slot, *d*, of a bracket, J, whereby provision is made for substituting a larger or smaller worm-wheel, according to the speed required, or certain of them. Upon either end of the main shaft B—that is, upon opposite sides of the machine—is a grooved cam, K, suitably shaped to give the necessary up-and-down actions and pauses to the needle-bar D, by means of a divided lever, L, working on a fulcrum, *d*, and adjustable by a slotted connection, *e*, to give more or less stroke to the needle-bar, the one division of each of said levers L being provided with a roller, *f*, entering within the grooved cams K, and such lever-divisions being connected, by rods *g*, through sliding wrists *g'*, to provide for the traversing movement of the carriage C with the needle-bar D, that works in vertical slots *h* in opposite sides of the carriage sides or cheeks. One of these rods *g* is extended downward, and in slotted connection below with a slotted bar, M, that is adjustable as a slide in or along an arm, M', on a shaft, N, to give more or less reciprocating motion, as required, to said shaft, that has adjustable bearings, and that, by means of levers O O and adjustable slotted bars P, gives the necessary reciprocating movements in line with the feed to the shuttle driver

or bar Q, which latter is arranged to slide in ways connected with the traversing carriage C, and in suitable relation with the shuttle-races i therein. The bars P, at their ends farthest from the levers O, are fitted to freely slide through pivoted or rocking connections k, carried by brackets on the under side of the front portion of the stationary table F, and are provided with boxes or bearings l intermediately of their length, through which rod or wrist like end extensions m of the shuttle-driver Q are free to slide in common with the traversing carriage C, and whereby the movement of said carriage does not interfere with the movement, in a transverse direction thereto, of the shuttle-driver Q. This forms a very simple and effective combination to provide for such two movements. The feed-rolls E and drawing-rolls G, both of which are suitably geared as regards their respective rolls, and said feed and drawing rolls united to work in unison by means of the endless chain H, and pulleys on the ends of certain of said rolls, have their pressure controlled by levers S and springs n. Motion is given to said rolls as follows: Upon the revolving shaft or stud c of the worm-wheel I is a spur, R, which gears with a wheel, T, to give intermittent revolving motion to a shaft, r. On this shaft r is a pattern wheel or cam, U, shaped on its face to accord with the pattern required, so far as the same is controlled by the feed of the material, but inclining in reverse directions circumferentially, so as to form a raised portion on one side of its axis, and a lowered portion on the opposite side thereof, whereby feeding motion is given alternately, once during each revolution, to the wheel U, to toothed dogs V V, which rest on and gear with ratchet-wheels W W on the shaft of one of the drawing-rolls G, and so that, as one dog V makes a series of intermittent feeding strokes on its ratchet W, the other dog V makes a corresponding series of slip or back motions over its ratchet W, thus keeping up a continuous intermittent revolving motion to the drawing-roll shaft, on which the ratchets are arranged. The dogs V V are thus alternately operated, through the pattern-wheel U, by means of adjustable levers Y Y, working on fulerums s, and springs t t, which latter keep the lower ends of said levers or rollers thereon in contact with the reversely-inclined acting-face portions of the wheel U.

On the same shaft, r, on which the pattern-wheel U is arranged to give motion to the feed, is another pattern or cam wheel, X, having an eccentric groove in its face, in which a roller, u, carried by a lever, A', fits. This lever, which is also adjustable as regards its fulcrum a', is in slotted connection above, by a pin, b', with the traversing carriage C, to give the requisite motion to the latter. In this way it will be seen that both the traversing carriage and the devices which feed the material are operated by the same shaft, r, and that, by suitably changing the

pattern-wheels U X for others of different shape, or of different diameters, to vary the relative velocities of the devices which feed the material, and of the carriage which gives a traversing motion while the material is being fed, the pattern to be quilted may be changed in shape and size as required.

The presser-feet B' are lifted at intervals, as required, and caused to press or bear down on the material for the necessary length of time, by the direct agency of the needle-bar D, operating in conjunction with springs c', attached to the projections from the backs of the presser-feet. Thus the presser-feet are fitted to freely rock on a rod, d', carried by a stationary cross-bar, C', of the carriage, to which bar are also attached the springs c', that pull upward on the backs of the presser-feet, to keep their front portions down on the material. On the face, or in front of and below this stationary cross-bar C', a slotted lifting-bar, D', is fitted, so as to be capable of sliding up and down, by means of uprights e' e' and guides or staples f' f'. This slotted lifting-bar D' is arranged to lie over the presser-feet, in front of their fulcrums d'; and the presser-feet are formed, each, with a lip, h', which passes through its respective slot in the lifting-bar D'.

Attached to the needle-bar D are projections i', which, as the needle-bar rises, catch under projections k' on the uprights e' of the lifting-bar, and raise the latter, which, acting under the lips h', lifts the presser-feet from the material, the presser-feet not rising until after the needles are free from the material, and descending to bear down on the material in advance of the needles penetrating the latter.

The advance row of needles b b are carried by slotted sliding holders G', on arms or projections on the face of the needle-bar D, whereby said needles may be adjusted in or out, relatively to the back row of needles, and be secured in position by set-screws S'. This adjustment provides for varying the pattern.

I claim—

1. The combination, with the ratchets W W on one of the feed or drawing rolls, of the reversely moving and reciprocating dogs V V, the levers Y Y, the springs t t, and the pattern-wheel U, constructed to advance from opposite sides of its axis, either dog alternately, substantially as specified.

2. The combination, with the same shaft, r, which carries the feeding-cam or pattern-wheel U, of the second cam X, the lever A', and traversing carriage C, essentially as described.

3. The combination of the partial screw H* on the shaft B, the worm-wheel I, the gears R T, and the two cams or pattern-wheels U X, substantially as specified.

4. The combination of the cams K K, the adjustable bars or levers L L, the rods g g, the traversing carriage C, and the needle-bar D, provided with wrists g' g', constructed to slide through eyes in the rods g g, substantially as

shown and described, and for the purpose herein set forth.

5. The combination, with the traversing carriage C, of the shuttle-driver Q, arranged to travel in ways on the under side of the carriage, transversely to the motion of the latter, and provided with wrist-like extensions m, which are fitted to slide through boxes or bearings l in the rods P, that operate the shuttle-driver, essentially as described.

6. The combination, with the rocking presser-feet B', having lips or projections h', of the sliding lifting-bar D', and the needle-bar D, con-

structed to lift the bar D' against the pressure of the springs c', substantially as specified.

7. The combination of the movable carriage C with the series of needles b b, arranged in rows, having the needles of the back row directly in rear of those of the front row, relatively to the feed or travel of the fabric, substantially as specified.

M. A. KING.
